LOCOMOTIVE BOILER FEED WATER HEATING SYSTEM AND APPARATUS

Joel S. Coffin, Jr., Englewood, N. J., assignor to
C-S Engineering Company, Englewood, N. J., a
corporation of Delaware

Application April 26, 1934, Serial No. 722,498

19 Claims. (Cl. 122—434)

This invention relates to the heating of boiler feed water, particularly for locomotives, and especially to the heating of a supply of water in the tender of the locomotive, from which hot water 5 can be withdrawn by the locomotive feed water pump and forced into the boiler.

One of the objects of the present invention is to provide a feed water heating apparatus wherein a supply of hot water is maintained in readiness 10 to be drawn through the pump and forced into the boiler whenever the pump is started in operation.

In accordance with the present invention the tender of the locomotive is provided with water compartments in which the water is heated and from which water is drawn and forced into the boiler. In a locomotive boiler water heating system it is desirable to maintain a supply of hot water at the inlet of the feed water pump. This 20 has been difficult to accomplish in prior tender water heating systems and at the same time maintain a reliable water supply. If the water withdrawal outlet, or pump inlet, is located at the bottom of a compartment the water above the 25 inlet is usually cold even though the compartment may contain heated water. If the said outlet is at the top of the compartment in the hot water zone the supply of water to the boiler fails if the water level is not maintained over the pump 30 inlet.

It is an object of the present invention to provide a tender feed water heating system wherein the entrance to the pump inlet is at the bottom of a heating compartment, and wherein the water 35 immediately above the inlet is caused to be heated, and also wherein the supply of water to the pump inlet is maintained irrespective of the water level in the heating compartments, until the tender runs dry.

A further object is the provision of a plurality of water heating compartments connected in series, the compartment directly connected to the pump inlet being small so that its entire contents are rapidly heated to supply hot water to 45 the boiler instantly the feed water pump is started in operation.

An important purpose of the present invention is to supply hot water at such a head above the boiler feed water pump and at such a temperature 50 that the pump can handle the hot water at full capacity. There is always some suction at the pump inlet and if the water temperature were close to the boiling point in the tank the water would boil in the pump inlet, due to the reduced pressure thereat, so that the pump would not

handle the water at full capacity. Furthermore, the pump may force highly heated water satisfactorily when the head above the pump is at a suitably high level and may not handle the same temperature water satisfactorily when the level 5 is lower. Hence one of the primary objects of this invention is to provide means to maintain a constant high level of water above the pump inlet and at the same time to keep the temperature of the hot water at a high value but below the 10 boiling point.

A further object of the invention is the provision of a boiler feed water heating system wherein a heating compartment for the boiler feed water is provided in which the water level is maintained 15 constant regardless of the operation of the boiler feed water pump and of the level of water in the main water space of the tender by a water forcing means as an injector drawing water from the main water space and forcing it into the heating compartment when the water level falls therein by the action of the boiler feed water pump, which is located below the water level in the compartment, and also thermal means responsive to the temperature of the water in the compartment is provided to maintain the water at 20 some value below the boiling point, so that the feed water pump can always handle the hot water satisfactorily.

A further object of the invention is the provision of a plurality of water heating compartments in the tender, the compartments being in communication at the tops and each having heating means therein and so arranged that as water is drawn from one compartment hot water from 35 the top of the compartment is caused to flow into the first compartment, thereby insuring a progressive flow of hot water to the boiler. A water forcing means is provided to keep the compartments full from water drawn from the main water space 40 of the tender. The outlet of the first compartment, which discharges to the pump, is located at the bottom of the compartment, and a further object of the invention is the provision of valves located at the bottoms of the compartments and 45 opening from one into the other and into the main water space of the tender so that upon failure to force water into the heating compartments, which results in an undue depression of the water level in the compartments below the 50 water level in the main water space, the water will flow under the head of the water in the main water space into the suction inlet, thereby insuring a supply of water to the pump as long as there is water in the tender.

It is a further object of the invention to have the water capacity of the two heating compartments, so related to the water capacity of the locomotive boiler between its permitted high and low water levels that if the pump is started when the water level in the boiler is at the low water level line there will be no appreciable amount of cold water forced into the boiler when the high water level mark is reached.

10 A further object of the invention is to heat the water in the heating compartments by the locomotive engine exhaust steam and to provide valves responsive to temperatures in the two compartments to control the flow of steam to 15 maintain a constant temperature of the water in the compartments.

A yet further object is generally to improve upon locomotive feed water heating systems and methods.

Fig. 12 is a schematic showing of a modified form of steam control valves.

45 The invention is here applied to the locomotive having the boiler 10, engine cylinder 12, and tender 14. Feed water is supplied to the boiler from a turbine driven centrifugal pump 16 located conveniently on the engine below the 50 bottom of the tender through a pipe 18 and check valve 20. The turbine 22 of the pump is supplied by steam through a pipe 24 and control valve 26 from the turret 28. The tender is of the type having its coal pocket 15 located between 55 two legs 17 and 19 of the water space 21, and the heating compartments of the present invention are conveniently located in one of the water legs 19 of the tender. The water leg of the tender has the bottom wall 30, front wall 32, 60 outer and inner side walls 34 and 36, respectively, and the top wall 38. In tenders where the two water legs are joined by a water space underneath the coal pocket the water leg in which the present invention is applied is separated 65 from the water space underneath the tender by a vertical partition wall, which wall as here shown, see especially Fig. 3, is the wall 35 extended down to the bottom wall 30. A vertical plate 40 extends transversely across the water leg between the side plates 34 and 36 and is in water tight connection therewith and forms a forward water heating and storage compartment 42. A rear water storage and heating compartment 44 is provided by a second plate 45 which extends across the water leg and is in

water tight connection with the walls thereof. The spacing between the plates 40 and 46 is materially greater than the spacing between the plate 40 and the front wall 32 so that the water capacity of the rear compartment 44 is materially greater than that of the front compartment 42. The wall 46 of the rear compartment extends up to and joins the top wall 38 of the water leg while the partition wall 40 is terminated a substantial distance below the top plate 38 so that the two compartments are in water communication at the top. This is an important feature of the invention. The plate 46 preferably has its rear face lagged with suitable heat insulating material 48, herein shown as 15 wood boards, to prevent the cooling off of the hot water in the compartment 44 by the cold water in the tender. The water leg has a rear-most partition wall 50 extending transversely thereacross provided with an opening traversed 20 by a screen 52 which prevents the passage of foreign matter to and through the heating compartments and into the boiler. Said partition plates 40 and 46 are provided with water tight doors 54 and 56 respectively which when open 25 permit passage of a workman into the compartments. The screen 52 is also carried by a door which can be opened for the same purpose. The water outlet 58 of the compartments is located at the bottom of the foremost or small heating 30 and storage compartment 42, the outlet water flowing through a valve 60 and a flexible hose bag 62 to the suction pipe 64 of the feed water pump 16. Check valves 66 are located at the bottom of the partition plate 40 and open to 35 admit the passage of water from the large rear compartment 44 into the small forward compartment 42 when the water level in the small compartment reaches an abnormally low point or below the level of the top of the partition wall 40. The partition wall 46 of the rear compartment is similarly provided with a series of similar 45 check valves 68 to allow water to flow into the rear compartment from the main water space of the tender when the water level in the rear 50 compartment becomes lower than the water level in the main water space of the tender. These valves assure a supply of water to the inlet of the pump for so long as there is water in the tender and in the event of a failure of the water forcing means for the heating compartments, presently to be described, to operate.

Water from the main water storage space of the tender is forced by a water injector 70 into the bottom of the rear compartment 44 during 55 the time that water is withdrawn from the compartments. Said injector is located at the rear of the partition wall 46 and between it and the screen wall 50 and discharges water through the middle one of the check valves 68 into the bottom 60 of the rear compartment 44. The injector is operated by pressure water from the pump 16 supplied through a pipe 72 leading to a float valve 74 which receives water through a pipe 76 connected to the high pressure outlet pipe 18 of the 65 pump. The float valve, see especially Figs. 1 and 8, is located in the upper part of the forward water heating compartment 42 and is adapted to be opened when the water level drops in the compartment and closed when the water level rises, 70 thereby to maintain a constant level of water in the two heating compartments. The float valve may be of any suitable construction but as herein illustrated comprises a shell 78 that has internal confronting bosses 80 that are journalled 75

upon the aligned ends 76a and 72a of the pipes 76 and 72. The ends of said pipes are closed and are provided with side ports 82 that can move into and out of register with cooperating ports 84 of the bosses 80 so as to control the passage of water through the shell 78 between the two pipes, depending upon the position of the shell. The shell 78 is fixed to and carries a float member 86 that is partially submerged in the water of the two heating compartments 42 and 44. The ends 72a and 76a of the pipes 72 and 76 are disposed below a cover 88, see especially Figs. 2 and 3, resting on the top wall 38 of the water heating compartment so that the float mechanism when disconnected from the pipes 72 and 76 can be withdrawn from the compartments. As thus arranged when the pump 16 is started in operation to withdraw water from the heating compartments and the water level therein descends the pressure water supplied at the pump outlet automatically actuates the injector 70 to force water from the main water space of the tender to the heating compartments. The capacity of the injector 70 is adapted to be at least equal to the capacity of the pump, so that the injector can maintain a constant level of water in the heating compartments irrespective of the level of water in the main water space of the tender. The water that actuates the injector is heated and the heat is utilized in the injector for heating the injected water so that there is very little loss of heat since the thermal efficiency of the injector is almost perfect.

Steam for heating the water in the heating compartments is taken from the exhaust steam chest of the locomotive cylinders 12 and is conducted rearwardly toward the tender through pipes 90 and non-return check valves 92, but one pipe and valve being shown, to the rear of the locomotive wherein the steam passes through a pair of flexible hose bags 94 and 96 into two pipes 98 and 100. Said pipes pass through the front wall 32 of the tender and into the water space and thence upwardly through the forward heating compartment 42 and through the top wall 38 and into a pair of steam control valves 102 and 104, the pipes 98 and 100 being connected by a pipe 106, see Figs. 2 and 3, to equalize steam flow and pressure in the two hose bags 94 and 96. The outlet of the valve 102 is connected through a pipe 108 that passes downwardly through the top wall 38 and into the forward heating compartment 42 where it communicates with a heater 110. Said heater is located in about the vertical middle of the forward compartment and comprises essentially a horizontal cylindrical conduit 112, see especially Fig. 6, the ends of which are closed removably by caps 114 and having small orifices 116 in the bottom thereof through which small jets of steam can pass into the surrounding water thereby to heat the water. The outlet of the valve 104 is connected to a pipe 118 which extends downwardly through the top wall 38 and is provided with two branches 120 that are connected with heaters 122, shown in detail in Fig. 7, which heaters are or may be identical and are preferably of the circulating injecting type. Each heater comprises a discoidal casing having vertically spaced upper and lower walls 124 and 126 providing between them an annular outlet 128. A partition wall or diaphragm 130 is located between the two walls and provides between them an upper steam chamber 132 and a lower water chamber 134. The steam branch 120 is in communication with the steam chamber 132

and a suction pipe 136 is connected with the water chamber 134 and depends below the casing and into the bottom part of the rear compartment and terminates above the bottom wall 30 thereof and in front of a baffle plate 138 that is interposed between the inlet of the suction pipe and the outlet of the injector 70. The steam space 132 of the casing is provided with an annular nozzle passage 140 which discharges steam into the annular opening 128 so that by injector 10 action it induces a flow of water up the suction pipe and into the passage 128 where the steam commingles with the water and is condensed and the water is heated. This type of injector creates a strong circulation of the water in the rear compartment. The flow of heating steam through the heaters is controlled by the aforesaid valves 102, 104, as determined by the temperature of the water in the heating compartments. In some application of my invention I may prefer to omit valve 104, and also valve 102, or to substitute therefor a manually operated valve or valves 105 as shown in Fig. 12 and to permit the exhaust steam when available to flow continuously into compartment 44 from pipe 106. The valves 102 and 104 are or can be identical and one is illustrated in cross section in Fig. 4, the valve comprising a casing 142 having an inlet 144 which receives steam from a pipe 98 and an outlet 146 which discharges steam into a heater 30 pipe 118. A partition wall or diaphragm 148 is located between the inlet and outlet of the valve and is provided with a valve seat 150 and a valve member 152 cooperating with said seat. The stem 154 of the valve member carries a piston 156 35 which is materially greater in diameter than the diameter of the valve 152. The piston is reciprocable in a cylinder sleeve 158 carried by the casing 142 and open to the steam inlet passage 144 and closed at the other end by a cover 160 so 40 disposed that there is a steam space 162 between the cover and the underside of the piston 156. The steam space is provided with an outlet 164 in the cover. The piston is provided with a leakage passage between the steam inlet 144 and the space 162, the leakage passage being herein shown in exaggerated form as a peripheral clearance space 166 between the periphery of the piston and the cylinder 158. A spring 168 bears against the piston tending when pressure conditions permit to raise the valve 152 off its seat. The outlet passage 164 of the steam space 162 is greater in area than the leakage passage 166 from the steam inlet into said steam space. Thus when the passage 164 is completely open to atmosphere the total pressure of steam is greater on the piston 156 than on the underside of the valve 152 and hence effects the closing of the valve and maintaining the valve closed. When, however, the outlet passage 164 is closed the steam pressure builds up in the steam space 164 through the leakage passage 166 to equalize pressure on opposite sides of the piston and hence the valve opens. The flow of steam through the outlets 164 of the two valves 102, 104 is controlled 65 by the valves 170, 172, each valve controlling a separate steam valve and being operated in accordance with the temperature of a separate heating compartment. The valve 170 is influenced by the temperature in the forward heating compartment 42 and controls the valve 102 that supplies heating steam to said compartment. The valve 172 is influenced by temperature in the rear compartment 44 and controls the valve 104 that supplies steam to said compartment. The valves 70 75

170 and 172 are or can be identical and one is illustrated in Fig. 5. These valves are of a common type having a bellows or diaphragm expanded and contracted by changes in temperature of the water in the associated compartment, as shown in Fig. 5, the valve comprising a casing having an inlet 173 and an outlet 174 and valve discs 176 interposed between the inlet and outlet and carried by a stem 178 fixed to one end of an expandable diaphragm 180. The arrangement is such that as the diaphragm or bellows expands downwardly the valve is opened and as the diaphragm is contracted the valve closes. The interior of the diaphragm of the valve 170 is connected through a flexible or other tube 182 with a bulb 184 located within the forward heating compartment 42. The bellows of the valve 172 is connected through a similar tube 186 with a bulb 188 located in the rear compartment 44. The arrangement is such that as the fluid within the bulb expands the associated diaphragm is caused to expand and operate the valve. The inlets 173 of the valves are connected through pipes 190 and 192, respectively, with the leakage outlets 164 of the steam regulating valves 102 and 104, and the arrangement is such that when the temperature of the water in a compartment rises to a suitable degree the temperature responsive valve is caused to open and effect the closing of the associated steam control valve. The control is also such that the degree of opening of the steam valves is controlled so as to tend to maintain a constant temperature of water in the heating compartments. With this arrangement when the temperature of water in any compartment drops the associated steam valve is opened to effect the heating of the water in the compartment. The arrangement is also such that the high temperature of the water is limited to a value such that, at the height of water in the compartments above the pump inlet, the pump can handle the hot water satisfactorily.

The two compartments are provided with a vent pipe 194. The valves 103 and 104 are located a substantial distance above the water level in the heating compartments and the outlet pipes 108 and 118 are provided with vacuum breaking valves 196 which admit air into the steam piping in the event of the formation of a vacuum there-in so as to prevent water from being drawn into the steam piping from the heating compartments.

The operation of the system is essentially as follows:

When the locomotive is moving and is using steam the water in the two heating compartments 42 and 44 is maintained at the desired elevated temperature below the boiling point by the automatic action of the temperature control steam valves 102 and 104. Thus when the pump 16 is set in operation to force water into the boiler hot water is immediately drawn into the pump. The lowering of the water level in the compartments due to the action of the pump causes the lowering of the float 86 which opens the associated valve to admit high pressure water from the pump into the nozzle of the injector 70, thereby to force water from the main water space of the tender into the compartments. The float thus acts to maintain the water level in the compartments substantially constant irrespective of the water level in the main water space of the tender. The water passed into the injector from the pump is hot and so warms the incoming water. The incoming water is heated and the hot water flows upwardly in that compart-

ment and over the top of the partition wall 40 into the forward compartment 42 so that the pump, when operating, is always supplied with hot water. When the temperature of the water in the compartments becomes reduced to a predetermined extent the steam valves 104 and 102 open to reheat the water. The capacity of the steam supply means is sufficient to heat the water fed to the boiler to the desired elevated temperature when the locomotive and pump are operating continuously for long periods. Under such conditions the water in compartment 44 becomes heated to a certain extent and that in compartment 42 is further heated to the desired temperature for boiler feeding.

Under conditions of totally intermittent operation such as may obtain in the case of a switching engine in which the boiler may be filled while the engine is standing and no steam is available for water heating, and in which full power may subsequently be exercised in hauling a train while no water is fed, my invention will be seen to be particularly adapted to effect the required feed water heating. Under such conditions I may proportion the capacity of the two compartments 42 and 44, so that their total capacity is approximately equal to the water capacity of the boiler between the permissible high and low gauge glass levels. When the engine is working and pulling the boiler level down from the high to the low gauge glass, the corresponding volume of water is being heated in the two compartments to the required temperature. First the forward or smaller compartment is heated to the required temperature and further heating therein becomes prevented by the operation of the thermostat. Subsequently the larger rear compartment becomes heated to the required temperature. The locomotive may then cease working and the pump may fill the boiler with heated water, leaving substantially cold water in the compartments, and the operation may be repeated.

Actually the operation of a particular locomotive is usually intermediate between continuous and intermittent operation and it will be seen that by the adoption of a small front compartment I am able to heat this to the thermostat shut-off temperature rapidly. If, in the above described intermittent operation, the pump is started before the complete body of water in both compartments has become heated, it will initially, at least, draw completely heated water from the front compartment. It will be seen that by properly proportioning the sizes of the compartments 42 and 44, I may secure the best operation for a particular locomotive service.

The check valves 66 insure a supply of water to the pump in the event of failure of the injector 70 to operate and thus assure a water supply for the boiler as long as there is water in the tender.

I claim:

1. Boiler feed water heating apparatus comprising two heating compartments connected at the top, a heater in each compartment, a water outlet at the bottom of one compartment and a water inlet at the bottom of the other compartment.

2. Boiler feed water heating apparatus comprising two heating compartments connected at the top, a heater in each compartment, a water outlet at the bottom of one compartment and a water inlet in the other compartment, the compartment associated with the water outlet be-

ing relatively small and the other compartment being relatively large in water capacity.

3. Boiler feed water heating apparatus comprising two heating compartments connected at the top, a heater in each compartment, a water outlet at the bottom of one compartment and a water inlet at the bottom of the other compartment, and means for maintaining a normal water level in said compartments above the bottom of the interconnection therebetween.

4. Boiler feed water heating apparatus comprising two heating compartments connected at the top, a heater in each compartment, a water outlet at the bottom of one compartment and a water inlet at the bottom of the other compartment, a boiler feed water pump connected with said outlet, water forcing means discharging through said inlet, a main water space supplying water to said forcing means, and means for maintaining a constant water level in said compartments irrespective of the water level in said main water space.

5. A boiler feed water heating apparatus comprising two compartments having an interconnection therebetween at the top, a water outlet at the bottom of one compartment and a water inlet at the bottom of the other compartment, a heater in each compartment, means for forcing water into said inlet, and means responsive to the level of water in one compartment for operating said forcing means to maintain a normal water level above the interconnection between said compartments.

6. A boiler feed water heating system comprising two water heating compartments connected at the top, a heater in each compartment, a boiler feed water pump having a suction pipe opening into the bottom of one of said compartments, means for forcing water into the bottom of said other compartment, said means being operated by the water pressure of said feed water pump, and means responsive to the water level in said one compartment for controlling the operation of said forcing means for maintaining a normal water level above the bottom of the connection between said compartments.

7. A boiler feed water heating apparatus comprising two water heating compartments having a vertical separating partition that terminates below the tops of said compartments so that said compartments are in communication above the top of said partition, a heater in each compartment, and means to effect a flow of water into the bottom of one compartment and upwardly therein and over the top of said partition and downwardly within and out of the bottom of said other compartment.

8. A boiler feed water heating apparatus comprising two water heating compartments having a vertical separating partition that terminates below the tops of said compartments so that said compartments are in communication above the top of said partition, a heater in each compartment, a boiler feed water pump having a suction pipe opening into the bottom of one compartment, water forcing means opening into the bottom of said other compartment, and constant level mechanism controlling the operation of said forcing means and governed by the water level in said one compartment.

9. A boiler feed water heating apparatus comprising two water heating compartments having a vertical separating partition that terminates below the tops of said compartments so that said compartments are in communication above

the top of said partition, a heater in each compartment, a boiler feed water pump having a suction pipe opening into the bottom of one compartment, water forcing means opening into the bottom of said other compartment, and constant level mechanism controlling the operation of said forcing means and governed by the water level in said one compartment and operative to maintain a normal water level above the top of said partition.

10. A boiler feed water heating apparatus comprising two water heating compartments having a vertical separating partition that terminates below the tops of said compartments so that said compartments are in communication above the top of said partition, a heater in each compartment, a boiler feed water pump having a suction pipe opening into the bottom of one compartment, water forcing means opening into the bottom of said other compartment, and constant level mechanism controlling the operation of said forcing means and governed by the water level in said one compartment, said forcing means having means by which it is operated by the high pressure water of said boiler feed water pump.

11. A boiler feed water heating system comprising a main water compartment, a heating compartment in which the water level is normally maintained higher than and independent of the water level in said main compartment, a heater for heating the water that is in said heating compartment, a boiler feed water pump receiving water from said heating compartment and having a suction pipe opening thereto, means responsive to the water level in said heating compartment for forcing water into said heating compartment from said main compartment to maintain a normal water level in said heating compartment, and means operative upon the failure of said forcing means to maintain a normal water level to admit cold water from said main compartment into said suction pipe without being heated by said water.

12. Boiler feed water heating apparatus comprising a main water space, two water heating compartments connected at the top, a heater in each compartment, a boiler feed water pump having a suction pipe opening into the bottom of one compartment, water forcing means for forcing water from said main water space into said other compartment, and means operative upon an abnormal depression of said water level below the connection between said compartments to establish communication between said compartments at the bottom thereof.

13. Boiler feed water heating apparatus comprising a main water space, two water heating compartments connected at the top, a heater in each compartment, a boiler feed water pump having a suction pipe opening into the bottom of one compartment, water forcing means for forcing water from said main water space into said other compartment, and means operative upon an abnormal depression of said water level below the connection between said compartments to establish communication between said compartments at the bottom thereof and also between said compartments and said main water storage space.

14. Boiler feed water heating apparatus comprising a main water space, two water heating compartments connected at the top, a heater in each compartment, a boiler feed water pump having a suction pipe opening into the bottom of one compartment, water forcing means for

forcing water from said main water space into said other compartment, and check valves located at the bottom of said compartments for admitting water from said main water space through said compartments into the inlet of said suction pipe when the water level in said compartments becomes abnormally low.

5 15. A boiler feed water heating system comprising two water heating tanks of unequal capacity interconnected at the top, a feed water pump drawing water from the bottom of one compartment, means for admitting water into the bottom of the other compartment, a heater in each compartment, and temperature responsive means separately associated with each compartment and influenced by the water temperature therein for controlling the operation of the heater in the associated compartment.

10 16. Boiler feed water heating apparatus comprising a large and a small water heating compartment communicating at the top, a steam heater in each compartment, a boiler feed water pump withdrawing water from said small compartment, thermo-responsive means governed by 15 the temperature of the water in said small compartment for controlling the supply of steam to the heater in said small compartment, and means for passing steam in a continuous manner whenever heating steam is available to the heater in 20 said large compartment.

25 17. A locomotive boiler feed water heating system comprising a main water compartment, water heating and storage means having means whereby the hottest water is in one part and the 30 coolest water is in another part of said storage

means, a boiler feed water pump drawing water from the hottest water part of the storage means, forcing means forcing water from said main water compartment into the coolest water part of said storage means and having means associated with it operative to maintain in said storage means a constant water level that is higher than in said main compartment, and heating means in 5 said storage means.

10 18. Locomotive boiler feed water heating apparatus comprising a cold water space, a heating compartment, a boiler feed water pump drawing water from said compartment, means for introducing water from said cold water space into said compartment at such a rate during each 15 operation of said pump as to keep the water level substantially constant in said compartment at such time, and means for heating said water after introduction to said compartment between pump operations.

15 19. Locomotive boiler feed water heating apparatus comprising a cold water space, a heating compartment in which the hot and cold water are in different parts thereof, a boiler feed water pump drawing hot water from the hot water part 20 of said compartment, means for introducing water from said cold water space into the cold water part of said compartment at such a rate during each operation of said pump as to keep the water level substantially constant in said 25 compartment at such time, and means for heating the water after introduction to said compartment between pump operations.

JOEL S. COFFIN, JR. 35
